UNITED STATES PATENT OFFICE

JACQUES KREISLER, OF NEW ROCHELLE, NEW YORK, ASSIGNOR TO JACQUES KREISLER & CO., A COPARTNERSHIP COMPOSED OF JACQUES KREISLER, EDWARD L. STERN, AND TOBIAS STERN, OF NEW YORK, N. Y.

CLASP FOR JEWELRY

Application filed February 23, 1929. Serial No. 342,063.

This invention relates to improvements in clasps and particularly to a clasp especially adapted for wrist watch bands of the flexible metal mesh type, whereby the band may be securely held in adjusted position when the clasp is closed and free to move through the clasp when the latter is open for adjustment.

The object of my invention is to provide a clasp for wrist bands which in closed position embraces the band and prevents it from further movement without in any way marring the delicate wire mesh of the band.

A further object of the invention is to provide a clasp of this character which when released and arranged in open position is provided with sufficient open space to permit perfectly free adjustment of the band through the clasp.

I accomplish these objects by means of the arrangement and combination of parts hereinafter described, set forth in the claims, and illustratively exemplified in the accompanying drawings, in which, Figure 1 is a plan 25 elevational view showing the application of my improved clasp; Figure 2 is a substantially longitudinal sectional view through the wrist band and clasp, the section being taken on lines 2—2 of Figure 1; Figure 3 is a sectional view taken on lines 3—3 of Figure 2; Figure 4 is a sectional view similar to Figure 3 except that the clasp is shown in open position; and Figure 5 is a perspective view of the clasp in open position and the end of the band to be engaged between the sides of the clasp members.

Referring to the drawings, 10 denotes a flexible mesh wrist watch band having its opposite ends provided with link portions 11 through which the wire bails of the watch case project. The band 10 according to the present invention consists of two sections, the one thereof terminating at its end opposite the link in a ring 12 which also carries the loop end of the other section designated 13. Of course, it will be understood that I do not mean to limit my invention to the two section construction as it will be readily seen that the band 13 may be lengthened and section 10 dispensed with by providing a link

corresponding to link 12 adjacent portion 11. In this way the band would consist of but one section. The section 13 of the band is attached at one end to the clasp while the other end as stated is threaded through the ring 55 12, back upon itself and through the clasp and finally ending in the link 11. To adjust the length of the band to accommodate different wrists and to allow removal of the band from the wrist by increasing its length 60 is all effected by the manipulation of the clasp which must be of a design to allow continual operation thereof without damaging the delicate wire mesh of the band.

The end of the band in section 13 which 65 is permanently attached to the clasp comprises a block of metal made up preferably of two cylindrical members 14 and 15, the latter may be solid if desired, and a U-shaped member 16 attached at its closed end to the 70 member 14 on its side opposite that occupied by member 15. The end links of the wire mesh are disposed between the arms of the member 16 and made fast by means of solder. The construction at the end of the band in 75 section 13, which is permanently attached to the clasp, may of course be varied so that the same may be stamped up from solder coated sheet metal and if desired one of the cylindrical members, for example 15, may be 80 dispensed with.

The clasp illustrated particularly in Figure 5, comprises an upper jaw 17 and a lower jaw 18. Both jaws 17 and 18 are substantially U-shaped pieces of metal, the upright 85 arms forming the sides. The lower jaw 18 is slightly smaller than the upper jaw 17 so that the sides of the former nest inside the sides of the latter. The jaws 17 and 18 hinge upon each other, the same being provided with a pintle pin 19 which projects through openings in the extreme ends of the sides. The closed top of the upper jaw 17 is the full length of the jaw itself, but the closed portion forming the under wall of the jaw 18 is cut away substantially one half of its length to provide an opening 20 of sufficient dimensions to freely accommodate a single strand of the band, as illustratively exemplified in Figure 4.

An assembly of the block at the end of the 100

section 13 and the clasp is made by placing the cylindrical member 14 with its bore in register with the openings in the sides of the nested jaws 17 and 18 and then running the 5 pindle pin 19 therethrough, as illustrated in Figure 2.

To release the grip of the clasp on the strand of the band running through the slot or opening 20, the two jaws are separated at 10 their free ends, the jaws assuming the respective positions shown in Figure 4, the block following the upper jaw 17 to substantially upright position thereby clearing the space above the opening 20 to permit the 15 flexible band to be drawn therethrough, without the slightest interference being offered by either jaw of the adjacent attached end of the band, and block. When the wrist band has been adjusted to the desired length, the 20 upper jaw 17 is closed over the lower jaw 18 with the flexible strand of the band disposed therebetween, as illustrated in Figure 3. The block, of course, having swung about the pindle with the upper jaw 17, is arranged 25 in position to bring the free side of the outer cylindrical member 15 which operates virtually as a cam, in position to rest in a transverse groove formed in the mesh of the band on its upper face, while the same or adjacent 30 groove of the under face of the same strand of band is arranged by the pressure of the cam surface of the block toward the inner edge of the cut away portion of the closed under wall of jaw 18. In this position the strand of 35 the band is firmly engaged against movement in either direction relative to the clasp without deforming the wire mesh of the wrist band and with the assurance that once the clasp has been closed there is no possibility of the 40 same accidentally opening up due to strain exerted by pull on opposite ends of the band. Further provision against disengagement of 45 the two jaws from their closed position is made by offsetting small lugs 21 adjacent the outer ends of the outside of the sides of the under jaw 18, as illustrated in Figure 5. When the jaws are closed, the lugs 21 spring the sides of the upper jaw 17 which are provided with slight depressions 22 to accommodate the lugs 21.

Having now described my invention what I claim as new and desire to secure by Letters Patent is:

1. A clasp for a flexible mesh wrist watch band, comprising a cam block rigidly attached to one end of the band and provided with a bore and a cam surface beyond said bore, upper and lower jaws pivoted to the cam block and to each other and provided 50 with means to embrace opposite faces of a portion of the strand, and a pindle projecting through one end of the jaws and through the bore of said block whereby one of the jaws in closed position will engage one side of the strand being pressed against it by the rela-

tive position of the cam surface of the block.

2. A clasp, as claimed in claim 1, in which the jaws are provided with upper and lower U-shaped members arranged with their closed ends forming the upper and under walls, the 70 under wall being cut away to form an opening greater in dimensions than the thickness of the strand, the side walls of the jaws being nested to accommodate the said pindle beyond the opening in the under wall, the said 75 cam of the block when the jaws are closed, being disposed to prevent movement of the strand between it and the adjacent end of the under wall.

3. A clasp for a wrist watch band, comprising upper and lower hinged jaws, and means for adjustably securing an end of the band thereto, and a cam block rigidly secured to the other end of the band and pivotally mounted between the jaws on 80 the hinged axis of the latter, one of said jaws being provided with an opening to permit free adjustment of the band through the opening when the jaws are open, the edge of the opening being capable of being engaged 85 by one face of the band pressed against it by the relative position of the cam block against the opposite face of the band when the jaws are closed.

4. A clasp for a flexible mesh wrist band, comprising a cam block for attachment to an 90 end of said band, a pair of jaws to clamp over the opposite end of the band, one jaw being cut away to permit free movement of the chain therethrough when the jaws are open, and a pivot projecting through the jaws and 95 cam block, said cam block moving about the pivot when the jaws close to engage and hold the chain between it and the portion of the jaw at the end of the cut out.

In testimony whereof he has affixed his signature.

JACQUES KREISLER.
